UNITED STATES PATENT OFFICE.

CHARLES BURGESS, JR., OF WENONA, ILLINOIS.

GAS-ENGINE.

No. 895,155.

Specification of Letters Patent.

Patented Aug. 4, 1908.

Application filed November 16, 1907. Serial No. 402,450.

To all whom it may concern:

Be it known that I, CHARLES BURGESS, Jr., a citizen of the United States, residing at Wenona, in the county of Marshall and State 5 of Illinois, have invented certain new and useful Improvements in Gas-Engines, of which the following is a specification.

The invention has reference to improvements in gas engines of the well known four-10 cycle construction, the principal object being to provide an internal combustion engine comprising a cylinder and a piston therein of the double acting or reciprocating type in which the gases are exploded at opposite ends 15 of the piston, the piston being hollow and having a port communicating with an opening through the cylinder wall and the piston-rod working free within a housing or tube which forms a communicating passage be-20 tween the crank chamber of the engine and the piston whereby a continuous circuit of a cooling medium, such as air, may be passed from the crank chamber around the full length of the piston-rod and within and 25 around the piston and then discharged through the cylinder wall, thereby preventing the overheating of the housing or tube, piston and piston-rod, which overheating of any of said parts frequently renders gas en-30 gines of this type inoperative.

In the accompanying drawings, Figure 1 is a vertical section of a single-cylinder engine embodying my improvements. Fig. 2 is a vertical section designed to show an air-35 pump in combination with an engine. Fig. 3 is a cross-section of a cylinder on the line 3—3 of Fig. 1, with parts removed. Fig. 4 is an enlarged detailed section of the piston, piston-guide and gland with parts broken 40 away and other parts in section.

Referring now more particularly to the drawings, 5 represents as a whole the cylinder having the usual outer casing 6 forming a water-jacket 7 and a crank case 8. Between 45 the crank case 8 and the cylinder 5 is secured a guide-cylinder 9 which is bolted to the crank case by means of bolts 10 and its upper end engaging a circumferential boss 11 formed on the outer casing 6. At each end 50 of the cylinder 5 is an explosion chamber 12 and 13 with the usual intake valves 14, 15, exhaust valves 16, 17, caps 18 carrying the spark plugs 19 that are secured to the intake side of the engine and the caps 20 carrying 55 the pet-cocks 21 on the exhaust side of the engine. The ducts 22 lead to the intake

valves for admitting the gaseous mixture thereto and the ducts 23 carry away the discharged gases, while 24 is the discharge port for the liquid in the water-jacket.

Within the cylinder is a double-headed piston 25 carrying the usual piston rings 26 at both ends thereof, the piston being hollow, except for the strengthening rods 27 each meeting at a point substantially central within the interior thereof to form an attaching point 28 for the piston-rod 29. The piston-rod is adapted to be secured to the said attaching point by means of threads and to be secured more firmly by the bolt 30. Said piston-rod extends through one end of said piston which is provided with an annular opening having an annular threaded boss 31 surrounding said opening and a sliding tube 32 or conductor for a cooling medium that is 75 threaded at one end and is adapted to engage the threaded boss 31 to secure said tube to said piston, the piston-rod being adapted to work within said tube. In the engine as shown, said tube 32 is adapted to have a vertical movement within the guide-cylinder 9 working through the gland 33 that is formed through the lower end wall of the cylinder and outer casing 6, the usual packing rings 34 being provided. It is to be understood that 80 the tube 32 is hollow, one end opening into the piston and its other end into the crank case. The piston is cored as shown at 35 and a series of ports 36 in the piston permit air coming through the tube 32 to pass out into 90 the chamber 37 that is formed by the cylinder wall and the cored portion of the piston. The cylinder wall is provided with one or more exhaust portions 38 whereby when the piston is moved to bring any part of the 95 cored portion thereof opposite the said ports, the air within the chamber will pass out through said ports 38.

Sliding within the guide-cylinder is a cross-head 39 to which one end of the piston-rod is 100 secured, and the connecting rod 40 is secured to the cross-head by means of the wrist-pin 41. The connecting rod is secured at its outer end to the crank 42 to which the two-part driving shaft 43 and 43^a are secured. 105 To the driving shaft 43^a is attached a gear 44 that drives the gears 45 and 46 which work upon the stems 47 and 48 of the exhaust and intake valve respectively, and the springs 49 are adapted to return said valves to their 110 seats.

Referring to Fig. 2, the gear 44 on shaft 43

drives the gear 46 which in turn is connected by means of a shaft to an air-pump 50 and a discharge pipe 51 connected to said air-pump conducts the air therefrom into the crank 5 chamber and guide-cylinder. 52 represents a balance wheel connected to the shaft 43. In operation air passes from the air-pump into the crank chamber and is forced from said crank chamber through the conductor or 10 tube 32 into the piston and around the same into the chamber 37 until said piston in its reciprocating movement brings the cored portion opposite the apertures or openings 38 whereupon the air passes out through the 15 cylinder wall, it being understood that by means of an air-pump there is a constant pressure of air within the crank chamber to force said air up through said tube 32. The object of forcing the air through the tube 32 20 is two-fold. First, it cools the gland 33, whereby an engine of the present construction is provided with a gland through which the piston-rod works that has two means of cooling the same, viz: the water jacket surrounding said gland and the air passing through said tube. This gland 33 is the portion of the engine subject to the most friction and the most heat. Secondly, the air serves 25 to cool the piston in that it passes into and around the same, but the primary object of the invention is to obtain in a double-acting engine a gland through which the piston-rod works that is prevented from being overheated.

35 The details of the construction of my invention may be modified without departing from the broad general principle thereof; and, without limiting myself to precise details of construction.

40 I claim:

1. The combination with a double-acting cylinder having discharge ports for a cooling medium, of a hollow piston in said cylinder having openings adapted to communicate 45 with said discharge ports, a crank-chamber, a crank and a piston-rod, a conductor for a cooling medium surrounding said piston-rod, one end of said conductor opening into said

piston and the other end opening into said crank-chamber, and means for maintaining 50 a continuous supply of a cooling medium in said crank-chamber, substantially as described.

2. The combination with a double acting engine cylinder formed with one or more lateral discharge ports for a cooling medium substantially centrally thereof, of a hollow piston in said cylinder having lateral openings adapted to communicate with said discharge ports of the cylinder, a crank chamber, a crank, and a piston-rod, a tube surrounding said piston-rod and connected at one end to said piston and at its other end extending into said crank chamber, and means for maintaining a continuous supply 65 of a cooling medium in said crank chamber, substantially as described.

3. The combination with a double acting engine cylinder, formed with one or more lateral discharge ports for a cooling medium 70 substantially centrally thereof, of a hollow piston in said cylinder having a cored portion and lateral openings thereto adapted to communicate with said discharge ports of the cylinder, a crank chamber, a crank, and 75 a piston-rod, a tube surrounding said piston-rod and connected at one end to said piston and at its other end extending into said crank chamber, and means for maintaining a continuous supply of a cooling medium in 80 said crank chamber, substantially as described.

4. The combination with a double-acting cylinder having discharge ports for a cooling medium, of a hollow piston in said cylinder 85 having openings adapted to communicate with said discharge ports, a crank chamber, a crank, a piston-rod, and a conductor for a cooling medium surrounding said piston-rod, one end of said conductor opening into said 90 piston and the other end opening into said crank chamber, substantially as described.

CHARLES BURGESS, JR.
